UNITED STATES PATENT OFFICE.

ELI OVERTON, OF UTICA, NEW YORK, ASSIGNOR OF ONE-HALF HIS RIGHT
TO NOAH A. LEWIS, OF SAME PLACE.

IMPROVEMENT IN FASTENERS FOR THE MEETING RAILS OF SASHES.

Specification forming part of Letters Patent No. 147,570, dated February 17, 1874; application filed
December 13, 1873.

To all whom it may concern:

Be it known that I, ELI OVERTON, of Utica, in the county of Oneida and State of New York, have invented a new Improvement in a Sash Lock, Holder, and Fastener; and I hereby declare the following to be a full, clear, and exact description of the same, reference being had to the accompanying drawings, with the letters of reference marked thereon, forming a part of this specification.

My invention is the lock, which is made of metal and secured to the top rail of the lower sash by means of a screw, which forms its axis. It has two hooks, the use of which is to engage the staple or staples on the face of the upper sash, while the other enters a slot or slots in the strip, which prevents a lateral movement of the lower sash. It has also an arm, which is enlarged at its end to form a bearing to the thumb or finger that operates it.

Figure 1 is a front elevation of a window as seen from the inside. Fig. 2 is a plan view or section on line *x x* of Fig. 1.

Similar letters of reference denote like parts in all the figures.

A is the frame of a window, having inner

and outer strips, and parting beads to form grooves for the sash to slide vertically and prevent a lateral movement of the same. B is the upper, and C the lower, sash. F is the lock or support, which is secured to the lower sash C by the screw *a*, which forms its axis. Staples or rests *b* are fastened to the upper sash at several points to bear against the hook *d* to hold the two sashes together, while the hook *e* enters the slots *f*, shown by dotted lines, in the strap H.

The lock or fastening is released by pressing the forefinger or thumb against the arm *g* and drawing it inward.

My invention is simple and effectual, as well as economical.

What I claim as new, and my invention, and desire to secure by Letters Patent, is—

The lock or fastening F, in combination with a series of staples or rests attached to the upper sash, and a series of slots in the inner side of the strap or bead, as and for the purpose set forth.

Witnesses:

ELI OVERTON.

I. BENEDICT,
CHAS. E. LEWIS.
